(57) **CLAIM**

The ornamental design for a multi-function tool for use by divers, as shown and described.

DESCRIPTION

FIG. 1 is a top and front perspective view of a multi-function tool for use by divers showing our new design;

FIG. 2 is a front view thereof;

FIG. 3 is a rear view thereof;

FIG. 4 is a top view thereof;

FIG. 5 is a bottom view thereof;

FIG. 6 is a left side view thereof.

FIG. 7 is a right side view thereof; and,

FIG. 8 is an alternative front view illustrating the tools which are normally secured in the interior of the housing.

1 Claim, 2 Drawing Sheets
